RETORET AND RETRORET SETTING

Clarence E. Hawke, Metuchen, N. J., assignor, by
mesne assignments, to The Carborundum Com-
pany, Niagara Falls, N. Y., a corporation of Del-
aware

Application October 21, 1936, Serial No. 106,867

8 Claims. (Cl. 263—37)

This application relates to improvements in retorts and retort settings. More particularly the application is concerned with vertical retorts composed of non-metallic refractories, and used for metallurgical purposes or for the calcination of minerals. The present application is a continuation in part of my copending application Serial No. 47,381, filed October 30, 1935. (U. S. Patent 2,067,085.)

10 In such industrial applications as have been indicated above, gases or vapors are often given off in great abundance as in the case of the refining of zinc or in the calcining of limestone. There are many difficulties in maintaining a reasonably gas or vapor tight structure in metallurgical and other retorts during prolonged periods of operation, especially where it is necessary to use non-metallic retorts.

15 Non-metallic refractories are extensively used where resistance to change of shape at high temperatures and chemical inertness at high temperatures are required. It is not possible to construct a retort of non-metallic refractory materials that will be absolutely gas or vapor tight.

20 Retorts can be built up of non-metallic refractory elements consisting of superimposed hollow one-piece sections. The walls of a retort can also be built up by using combinations of refractory shapes with both horizontal and vertical joints which can be lapped or which can have tongue and groove connections. The sections or elements of a retort can also be cemented together. Such structures can be made reasonably tight and will show little or no gas or vapor leakage,

25 age, provided pressures are balanced within an inch or two of hydrostatic pressure. Such retorts, however, will not stand prolonged periods of operation without developing leaks either through the opening of the vertical joints, or because of the development and opening of cracks in the body of the refractories employed.

30 I have discovered that, in retorts of the type just described, little or no trouble is caused by the opening of horizontal joints or by the development or opening of cracks extending in a horizontal direction. This is due to the fact that the load imposed upon the refractory elements by the upper portion of a retort (including the portion of the retort which extends beyond and above the heating chamber) prevents the opening of horizontal joints or cracks and the development and opening of cracks extending in a horizontal direction.

35 Among the refractories which are most useful for high temperature work may be mentioned

silicon carbide, which has a high thermal conductivity (for a non-metallic refractory) and which retains great strength to compressive loads at the temperatures to which retorts are ordinarily subjected. This characteristic permits the use of this material in thin sections. Even this refractory is liable, however, to the development of hair-line cracks during prolonged periods of operation in which strains are produced by non-uniform heating or by rapid changes in temperature or by changes in local pressure. Such causes are likely to produce changes in volume which are not uniform throughout a given refractory element. The strains so produced must be relieved, and are relieved when the refractory element cracks or fractures. These cracks may not be visible when they first occur on account of the minute thickness of the opening produced. They will open up to a greater extent during prolonged periods of heating unless some force is applied to prevent the opening.

40 In the case of a vertical retort therefore, the fine cracks which occur in a horizontal direction are not likely to open up to any serious extent because of the superincumbent weight which tends to close the openings. The case is quite different with vertical cracks. This invention is concerned principally with the development of practical means for preventing vertical cracks from opening up in retorts built of non-metallic refractories.

45 For purposes of illustration my invention is described with reference to vertical retorts having a rectangular cross-section. The type of retort has long sides (as illustrated in the accompanying drawings) and narrow ends, the heat being transmitted from sources of heat situated outside of the opposite side walls.

50 In the accompanying drawings:

Figure 1 shows a horizontal section of a retort mounted in a furnace, the section being taken on the line I—I of Fig. 2;

Figure 2 is a fragmentary sectional elevation taken on the line II—II of Figure 1;

Figure 3 is a fragmentary horizontal section taken on the line III—III of Figure 4 and illustrating a modification of the means used for applying pressure to the end walls;

Figure 4 is a fragmentary sectional elevation taken on the line IV—IV of Figure 3;

Figure 5 is a fragmentary horizontal section illustrating means for facilitating movement of a compression member in a vertical direction.

where such movement is desirable to reduce stresses resulting from temperature changes;

Figure 6 is a fragmentary horizontal section of a retort and adjacent setting, the end of the retort shown being oppositely disposed to that shown in Figure 5;

Figures 7 and 8 are fragmentary elevations partly in section illustrating means for applying horizontal forces to pairs of compression blocks 10 which are in contact with end walls of the respective retorts, the form of the joints between adjacent tiles of the retorts being different in the two views;

Figure 9 is a horizontal section of a retort and 15 of part of the setting and shows side walls of the retort which can expand or contract horizontally independently of the end wall shown at the left; and

Figure 10 is a view similar to Figure 9 but showing weighted crank means for applying horizontal forces to the side walls instead of spring means.

Referring to the drawings in detail there is shown in Figure 1 an elongated retort 2 whose sides 3 are made as long as practicable. Heat is transmitted to the material inside the retort through these long sides from combustion chambers 4. The distance between the side walls of the retort may vary from 2 inches to 18 inches depending upon the process involved. The effective heating of the material within the retort will not be much affected by the length of the walls 3, that is by the horizontal dimensions of the heating surfaces exposed to the combustion chambers. On the other hand if the distance inside the retort between the side walls is too great, the materials near the wall of the retort will be overheated before the materials in the center of the retort reach the desired temperature. The optimum distance between the side walls will depend on the thermal conductivity of the materials under treatment.

It has been found that little or no trouble occurs through cracking of the refractories in the end walls 5 since these walls are not exposed to the combustion gases and are also of relatively small horizontal dimensions, so that it is not usually necessary to use vertical joints in these end walls 5. The difficulties described above have been experienced in the side walls which are usually several feet in length and which therefore have to be built up from tiles with vertical as well as horizontal joints. While in some of the views the retorts have been indicated without vertical joints, vertical cracks are likely to form during the operation of the retorts. One of the objects of the present invention is to prevent such cracks from opening up.

For efficient operation the side walls of the retort have to be built of a material having a high thermal conductivity while the walls 6 of the combustion chamber are built of a poorly conducting refractory such as fire-clay. As these two types of materials have in general different rates of expansion, it is essential that the retort should not be rigidly tied in with the structure of the setting, for if this is done the entire retort structure may be subjected to such strains as will cause destructive cracking of the refractories and the opening up even of horizontal joints. It is impractical therefore to hold the retort in compression from the sides by rigidly tying the retort structure in with the structure of the setting.

In the practice of my invention I apply pres-

sure in a horizontal direction to either one or both of the narrow ends of the retort by compression means attached to the outside structure of the retort setting. For example, in Figure 1 the movable blocks 7 and 8 are urged toward the respective ends of the retort by means of the springs 9 and 10. The amount of compression in the springs may be adjusted, for example by rotation of the member 12 which is threaded in the cap 13. As indicated in Figure 2 10 individual pressure-applying means may be used on a number of superimposed tiles in the end walls.

In the modification shown in Figures 3 and 4 15 the end walls of the retort are pressed with the aid of blocks 1', which in turn are pressed by means of weighted levers such as that indicated at 14. Pneumatic or hydraulic pressure devices may also be utilized, the hydraulic pressure being cushioned by means of a spring or by means of 20 compressed air, as illustrated diagrammatically in my U. S. Patent No. 2,067,085.

Horizontal forces should be applied to a sufficient number of the end wall elements to prevent any vertical cracks or joints from opening up in 25 the side walls as the result of internal pressures produced by the load in the retort or by the development of gases or produced as the result of the expansion and contraction of refractories when heated and cooled through extensive ranges 30 of temperature. The means used for applying these horizontal forces must be flexible enough to absorb the normal expansion of the refractories caused by the application of heat thereto and also flexible enough to maintain the horizontal 35 pressure in the event of any contraction due to cooling. In the case of the modification shown in Figures 3 and 4 the horizontal forces are applied through rollers 15 which are rotatably mounted in a lower extension of the lever 14. 40 The end walls are therefore not prevented from vertical expansion or contraction by their contact with the pressure-applying means. Where no such rollers are shown (as in Figures 1 and 2) the application of horizontal forces can be omitted 45 during the heating up period until the retort is brought to operating temperature. The horizontal forces are then applied by tightening up on the threaded bolts 12 until the desired compressive force is obtained. With this arrangement, 50 the spring pressure should be released before the retort is cooled.

In the modification shown in Figure 5 provision is made for the movement of the compression member 1' in a vertical direction, where, 55 for example, relief is needed from strains due to changes in temperature. In this case the rollers 18 are carried by brackets 19 which are in turn securely attached to the supporting members 21 of the retort setting. The plate 22 (to which the compression member 1' is attached) is thus permitted to move in a vertical direction during expansion or contraction of the retort relatively to the supporting members 21.

Referring to Figure 6, one end of a retort may 65 abut against rollers 23 which are supported on the retort setting while the opposite end of the retort is pressed by the resilient means shown in Figure 5, which means is vertically movable with respect to the adjacent setting as explained 70 above.

In the modification shown in Figure 7 means are shown for applying a horizontal force to two compression blocks located adjacent an end wall of a retort by means of a single force mecha- 75

nism. In this case a weighted lever mechanism (of the bell-crank type) is indicated in the drawings, but other means such as springs or hydro-pneumatic or pneumatic means or hydraulic means (cushioned by springs) may be used for applying the horizontal forces, as illustrated diagrammatically in my U. S. Patent 2,067,085.

The modification shown in Figure 8 is similar to that shown in Figure 7 except that the form 10 of joint between the tiles that compose the end walls and side walls of the retort is different.

In the modification shown in Figure 9 horizontal 15 pressures are exerted on the side walls through terminal blocks 34. The joints in the end wall that run parallel to the length of the retort are sealed by means of loose packing in the chambers 35. Gravity forces this packing 20 against the members 34 and causes a seal between the members 34 and the intermediate portion of the end wall and also between the members 34 and the adjacent retort setting.

As has been indicated above, the walls of the retorts are made of a non-metallic refractory having a low coefficient of thermal expansion and 25 a high degree of mechanical strength at high temperatures, such as bonded silicon carbide or recrystallized silicon carbide. Other refractories having a thermal conductivity greater than 0.006 calorie/cm³/sec./°C. may be used if they possess 30 the required mechanical strength, resistance to spalling and chemical inertness. The walls of the retort setting can be made of fire-clay backed with steel beams as indicated in Figure 1 of the drawings.

35 While I have described several methods by which the invention may be applied to vertical retorts, the principle underlying these methods is applicable to a still wider range of retort types and arrangements with their associated settings. 40 The drawings are intended to illustrate the practicability of the application of the invention in a variety of forms.

I claim:

1. A furnace for the heat treatment of materials comprising an elongated retort of rectangular horizontal cross section and having extended side walls for heat transmission from combustion chambers located on each side of the retort and having narrow end walls joining said side walls, 45 said end walls being shielded from the combustion gases, an outer furnace wall surrounding the retort and the combustion chambers, said outer wall having a movable section of superimposed blocks adjacent one end of the retort, and a plurality of weighted bell-crank levers for exerting horizontal forces against the adjacent end of the retort and tending to close vertical cracks in the side walls of the retort.

2. The furnace structure described in claim 1 50 in which the bell-crank lever compression mechanism transmits pressure through a member mounted for slidable movement in a vertical direction with respect to the outer wall of the furnace.

65 3. A retort having side walls for heat transmission from exterior heating sources and end walls contacting with the retort setting, and

automatically controlled means disposed between the setting and a terminal portion of each side wall for applying independently to each side wall horizontal pressure tending to close vertically disposed joints and cracks.

5

4. A retort having side walls for heat transmission from exterior heating sources and end walls contacting with the retort setting, means disposed between the setting and a terminal portion of each side wall for applying independently to each side wall horizontal pressure tending to close up vertically disposed joints and cracks, and cavities adjacent to terminal portions of the side walls containing finely divided material for sealing under the action of gravity the side walls 15 with respect to the end walls and the retort setting.

10

5. A furnace for the heat treatment of materials comprising an elongated retort of rectangular cross section having extended side walls for 20 heat transmission from combustion chambers located on each side of the retort and having narrow end walls one of which fits loosely between said elongated side walls, an outer furnace wall surrounding the retort and the combustion 25 chambers, said outer furnace wall having two movable sections of superposed blocks in contact with the respective loosely fitted ends of the side walls, and yieldable means for pressing said side walls of the retort in a horizontal direction.

30

6. A furnace for the heat treatment of materials comprising an elongated retort of rectangular cross section having extended side walls for heat transmission from combustion chambers located on each side of the retort and having 35 narrow end walls one at least of which fits loosely between said elongated side walls, an outer furnace wall surrounding the retort and the combustion chambers, said outer furnace wall having two movable sections of superposed blocks in 40 contact with the respective loosely fitted ends of the side walls, yieldable means for pressing said movable sections of the outer wall against side walls of the retort in a horizontal direction, and cavities adjacent to terminal portions of the side 45 walls containing loose granular material for sealing under the action of gravity the side walls with respect to the end walls of the retort and with respect to the outer furnace wall.

50

7. A retort having side walls for heat transmission from exterior heating sources and end walls contacting with the retort setting, and gravity controlled means disposed between the retort setting and a terminal portion of each side wall for continuously applying independently to 55 each side wall horizontal pressure tending to close vertically disposed joints and cracks.

55

8. A retort having side walls for heat transmission from exterior heating sources and end walls contacting with the retort setting, and resilient means disposed between the retort setting and a terminal portion of each side wall for continuously applying independently to each side wall horizontal pressure tending to close vertically disposed joints and cracks.
